UNITED STATES PATENT OFFICE.

CARL COLFELT AND ROBERT COLFELT, OF SHERWOOD, OREGON.

CHOKER-HOOK FOR HAULING LOGS.

No. 888,308.

Specification of Letters Patent.

Patented May 19, 1908.

Application filed February 28, 1908. Serial No. 418,382.

To all whom it may concern:

Be it known that we, CARL COLFELT and ROBERT COLFELT, citizens of the United States, and residents of Sherwood, Washington county, State of Oregon, have invented a new and useful Improvement in Choker-Hooks for Hauling Logs, of which the following is a specification, reference being had to the accompanying drawings as constituting a part thereof.

This invention relates to the cable which is looped around a log for the purpose of fastening the same to the hauling cable, by which the log is to be dragged along the ground; and our invention has for its object to so contrive the choker-hook and to combine means therewith as to render the same more convenient to use, and also to so arrange the parts that when once the choker-hook has been adjusted on the log it cannot come accidentally undone.

Our invention to this end comprises the arrangement and combination of parts illustrated in the drawings above referred to, in which,

Figure 1 is an elevation of our choker-hook complete, showing how the same would be arranged when encircling a log to be hauled thereby; and Fig. 2 is an elevation of what we term the link-and-hook, constituting a part of our choker-hook; this figure also illustrating that a portion of the link-and-hook is removable, so as to facilitate the placing of said link-and-hook upon, and the removal of the same from the choker-line.

Describing now, specifically, the parts entering into the construction of our invention, and referring to the reference letters in the drawings: that portion of our invention which comprises what we have termed the link-and-hook consists of a yoke *a*, provided with a pivoted bar *b*, and a swivel *c*, said parts *b* and *c* constituting a sort of universal joint. To the swivel *c* is fastened a chain-link *d*, and to the latter is secured a hook *e*. The point of the hook *e* is made with lateral fluke-like projections *f*, *f'*, to prevent the accidental release of the eye *g* of a cable *h*. The cable *h* can be made of any convenient length, usually about thirty feet, and is provided at its opposite end with another eye *g'*. The yoke *a* is apertured to receive a bolt *i*, by which is removably secured a sleeve *j*. Our

link-and-hook is attached and removed from the choker-cable *h* by the removal of the sleeve *j*, slipping the cable through the opening *j'* of said sleeve, and then assembling and fastening the parts together as mentioned. The eye *g'* prevents the cable *h* from slipping through the sleeve *j*, and also enables the attachment of our choker-line to the hauling cable.

In hauling the choker-line back into the woods, preparatory to hauling further logs, the eye *g* of the choker-line, being detached from the hook-member *f'*, is then fastened to the hauling cable, and is pulled back with the latter. The edges *j* are made flaring so as to cause the sleeve *j* to run more readily on the choker-line *h*. To provide for the case of a break in a choker-line, a spare choker-line, like *h*, should be on hand, to which our device can be readily attached as described. If there should be a break in the link-and-hook part, the choker-line *h* would not have to be cut and spoiled to remove the broken part, but the latter would quickly be removed from the line and another link-and-hook substituted in its place.

We claim:

1. In a choker-hook, the combination with a choker-cable having eyes formed at its ends, of a clip-like sleeve made with perforated extremities, a yoke removably pivoted to said extremities, a bar pivoted in said yoke, a swivel-eye pivoted in said bar, and a link-and-hook attached to said swivel-eye.

2. In a choker-hook, the combination with a choker-cable having eyes formed at its ends, of a clip-like sleeve made with perforated extremities, a yoke removably pivoted to said extremities, a bar pivoted in said yoke, a swivel-eye pivoted in said bar, a link-and-hook attached to said swivel-eye, and fluke-like projections on the point of said hook, for the purpose described.

3. A link-and-hook adapted to be used in connection with a choker-cable and comprising in combination a clip-like sleeve adapted to be placed on said choker-cable and made with perforated extremities, a yoke removably pivoted in said extremities of the sleeve, a bar pivoted in said yoke, a swivel-eye pivoted in said bar, and a link-and-hook attached to said swivel-eye.

4. A link-and-hook adapted to be used in

connection with a choker-cable and comprising in combination a clip-like sleeve adapted to be placed on said choker-cable and made with perforated extremities, a yoke removably pivoted in said extremities of the sleeve, a bar pivoted in said yoke, a swivel-eye pivoted in said bar, a link-and-hook attached to said swivel-eye, and fluke-like projections on

the point of said hook, for the purpose described.

CARL COLFELT.
